UNITED STATES PATENT OFFICE

FRIEDRICH MERK, OF FRANKFORT-ON-THE-MAIN, GERMANY

TELEPHONE SYSTEM

Application filed December 3, 1927, Serial No. 237,556, and in Germany December 4, 1926.

This invention relates to improvements in automatic telephone exchanges, and more particularly to the so-called connectors used in public telephone systems for establishing 5 the so-called long distance or toll line connections, the same connectors being applicable likewise for local calls and upon correspondingly changing the circuit arrangements also for ordinary and preferred local 10 connections.

For long-distance or toll-connections as distinguished from local connections, the following special conditions are in question:

(1) Local connections are to be broken to 15 favor a toll call after a preliminary warning has first been given to the speaking subscribers on the local line.

(2) Subscriber lines already busy with a toll call are to be closed to local and other 20 toll calls.

(3) The toll operator must be advised by signals whether or not a line called is free or busy with a local or toll call.

(4) The connections of local subscribers 25 to the toll exchange must be such that the subscribers can give flash signals to the toll operator by jogging the receiver hook, while the toll operator must be able to repeat bell calls to a subscriber who may prematurely 30 hang up his receiver after answering the first call.

It is to be assumed that the connectors are provided (as usual) with a three-wired multiple contact bank and that the subscribers' 35 lines have been connected to this contact bank without intermediate interruption points.

Heretofore it was assumed that these conditions could best be satisfied by preliminarily preparing the toll-connections by adjusting 40 the final selectors and subsequently closing the talking circuit by a switching operation by the toll operator, independently of the adjusting movement of said selectors. However, the introduction of this arrangement to 45 practice has led to such very complicated and expensive selector arrangements that it is preferred (for economical reasons) in most of the larger exchange systems, to effect toll-connections by means of manually operated 50 toll boards, while in smaller stations (such as

sub-stations and rural or land-stations) in which operators cannot be present continuously, disconnection by the toll exchange has not been used.

According to the present invention, the 55 selectors are controlled and the connections for toll calls are effected by a single continuous operation (in a similar manner to local connections) in such a manner that in both cases the switching operations following the setting of the selector are always made automatically immediately after the setting operation.

The object of this combination of the operations in the final selectors or connectors, both 60 for local calls and toll calls, is to utilize the same switching means in both cases. According to the arrangement in use heretofore, the switching means which come into operation automatically in the case of local calls, 65 after the final selectors have been set to ascertain whether the called subscriber's line is free or busy with a local call, for locking the lines and for ringing up the subscribers must be rendered inoperative and replaced by other 70 switching means controlled by the toll operator, whereas the arrangement according to the present invention makes it possible to use the same automatic connectors even for toll-connections, these arrangements being made 75 dependent on a toll testing and locking relay 80 for toll-connections.

The main object of the present invention is to so simplify the final selectors or connectors for the toll traffic that although the same selector switches are used, it is possible to break the local connection at the toll exchange when toll calls are received. The control of the final selectors is also simplified in such manner that it may be effected by the toll operator without any difficulties. Toll-connections are effected by the toll operator in the same manner as local connections by simply selecting the wanted subscriber's number without any further additional switching 90 operation.

A particular advantage of the invention resides in the fact that it is unnecessary to preliminarily "busy" the selector switches 95 and connecting or trunk lines for a long time, 100

as has heretofore been the case in initiating or establishing toll calls.

5 A further advantage of the present invention over prior arrangements resides in the fact that it entirely fulfills the aforementioned conditions, whereas the conditions are only partly fulfilled by the prior art arrangements.

10 The invention will now be described with reference to the accompanying drawings showing diagrammatically an embodiment of the invention, wherein:—

15 Fig. 1 shows in a system embodying the invention, the position of a toll operator with an incoming toll line L2 and an outgoing toll line L1 and a cord line for connecting them.

Fig. 2 shows the circuit arrangement of a final selector according to the invention controlled from the toll operator's position.

20 Fig. 3 shows a local connection made between two subscribers No. 23 and No. 34 over a so-called line selector and a final selector or connector.

25 The final selector or connector LW (Fig. 2) is in its constructional arrangement assumed to be a so-called panel switch board selector having 100 lines divided into groups of 10 lines each. a23, b23, c23 is one of these lines against which the wiper unit aII, bII, cII of the final selector or connector may be 30 adjusted, e. g. the line of the subscriber No. 23. The connector has a separate brush or wiper set or unit for each group of 10, i. e., 10 wiper units in all, which are all secured 35 to a single brush-carrying rod, and which are all connected in parallel. These wiper units may be made operative or inoperative selectively by a spreading and closing action.

30 A single switching magnet H produces, by 40 a stepwise lifting of the wiper rod, the selection of a group, the selection of one single line of the selected group and the release of the connector when the conversation is over. For obtaining this result, the magnet receives 45 three successive series of current impulses. To select for instance the lines a23, b23, c23, H is first energized twice and by this the wiper rod is lifted to such an extent that the wiper unit aII, bII, cII will be moved just opposite the second group of lines. In this position 50 a short energization of the brush set selecting or tripping magnet S will cause the brush set aII, bII, cII to be closed. By three further selecting impulses through the magnet H, 55 the brush-carrying rod is further lifted and the closed brushes of the set are brought into contact with the lines a23, b23, c23. At the end of a conversation the magnet H is switched over into an interrupter circuit, 60 causing a further lifting of the brush-carrying rod up to its end position from which it is caused mechanically to fall to its initial position. During this further automatic lifting of the rod, the brush set aII, bII, cII, 65 co- 70 operates with a fixed spreading member

which again restores the wipers to their initial spread or open position. The invention is not limited to this particular construction of the connectors. For a more specific disclosure of the constructional arrangement of connector switches of this character, reference is made to my co-pending application Serial No. 208,002, filed July 23, 1927, for selectors.

75 A limited number of relays is sufficient for controlling the connector switch LW by reason of the simplification of the circuit arrangement according to the present invention. A and B are two line relays connected to the line L1. Y is a line relay arranged at the 80 outgoing line side of the connector, PI is the usual testing relay to determine whether the selected subscriber's line is free or busy with a local connection. For testing the lines for "busy" for a toll-connection, a separate relay PII is used having one lightly and one heavily acting armature and two corresponding coils. This relay is the only additional member rendering the circuit arrangement (which is otherwise exactly the same as for a connector 85 for local traffic) suitable for toll traffic. The further relays R, Q and V are auxiliary relays, V being a slow release relay.

90 The relays are designated by capital letters and the contacts belonging to them are shown 95 on horizontally extended dotted lines passing through the axes of the corresponding relays. There are also provided (in the usual manner) a so-called foot or head off-normal contact k of the connector, which varies its position as soon as the brush-carrier leaves its 100 position of rest, and a contact w closed by the brush-carrier when leaving its position of rest, but opened again when the uppermost position is reached and remaining open during the downward movement of the rod. The contact of the magnet S is so arranged that when closed, it remains closed until the selector is released, even if the magnet S is de- 105 energized.

110 The setting of the brushes of the final selector or connector, for example onto the line of the subscriber No. 23, is effected from the toll operator's position in such a manner that by means of a number of dial or another impulse- 115 transmitter in the a-line with contact 11, two short circuit interruptions are given for the tens selection and thereafter three short interruptions for the units selection, whereas in the b-branch a somewhat more extended in- 120 terruption is effected at contact 12 following as a controlling impulse the tens impulses as well as the units impulses. During the selecting actions the a- and b-lines are also connected together by the contact z behind the impulse contact 11 and 12 by which short circuiting the impulses are prevented from being 125 heard at the other side of the operator's cord circuit.

130 When the line L1 is engaged by introducing

the plug of the operator's cord circuit, the relays A and B are energized in addition to the relay R by the following circuit:

- 5 + pole of battery, right hand outer front contact of relay A, foot contact *h*, relay R,
- pole of battery.

While the impulses are being transmitted over the *a*-branch, the relay A, in agreement with the dialing impulses is quickly deenergized twice and three times respectively, and after each impulse series, the relay B is once deenergized for a somewhat longer time. By closing its left hand back contact, the relay A transmits a corresponding number of impulses to the lifting magnet H in a circuit:

- 10 + pole of battery, right hand middle front contact of B, left hand contact of R, left hand outer front contact of B, left hand back contact of A, coil H to - pole of battery.

20 When the magnet H is energized, the brush-carrier is raised first two and then three further steps.

After the first two lifting steps, the brush set *a*_{II}, *b*_{II}, *c*_{II} is adjusted opposite the contacts of the second line group and is ready for the tripping action or closing in this position. The tripping action is produced by the controlling impulse following the tens selection impulses as on account of the deenergization

30 of the relay B a circuit is closed temporarily for the brush tripping magnet S, as follows:

- + pole of battery, right hand outer front contact of A, right hand outermost back contact of B, right hand outer front contact of R,
35 right hand outer back contact of V, coil S,
- pole of battery.

The contact of the relay S is closed and kept closed until the final selector is released. Therefore, when the relay B is again energized, the slow release relay V is energized by a current in the following circuit:

- + pole of battery, right hand outer front contact of A, right hand inner front contact of relay B, front contact of S, coil V to - pole
45 of battery.

The relay R has remained energized during the first deenergization of B by a circuit:

- + pole of battery, right hand outer front contact of A, left hand back contact of V,
50 right hand inner front contact of R, coil of R to - pole of battery.

From the moment that V has been energized the relay R is controlled solely by the relay B.

55 After the three further lifting steps, the brush set *a*_{II}, *b*_{II}, *c*_{II} contacts with the line *a*23, *b*23, *c*23. The relay B again deenergized by the controlling impulse following the unit impulses finally deenergizes at its inner right

60 hand front contact the relay R. Therefore, the electromagnets H and S cannot be energized again. The final selector adjusted from the toll exchange has now been set and all further switching operations are automatic sequences of the said ordinary second

controlling impulse. The action of the two testing relays PI, PII switched on by this controlling impulse, which will be described hereinafter is independent of any control of the toll operator and is only controlled by the 70 momentary state of the selected line *a*23, *b*23, *c*23 of the subscriber No. 23. Three different conditions may arise:

(a) *When subscriber's line is free*

In order that this condition will be understood it must be assumed that the local connection illustrated in Fig. 3 by the adjustment of a selector W1 does not exist.

The last controlling impulse effects, by 80 means of the deenergized relay B, first an ordinary testing of the line No. 23 to ascertain whether it is free or locally "busy" by means of the relay PI, and a moment later the "toll test" by means of the relay PII. The relay 85 PI is brought into circuit by the relay B directly at its right hand outermost back contact, whereas PII is brought into circuit by means of the slow release relay V deenergized by the relay B at its right hand innermost 90 front contact. In order that V will definitely release its armature, the controlling impulse has been chosen sufficiently long as above described.

The testing circuit for the relay PI is as 95 follows:

- + pole of battery, right hand outer front contact of A, right hand outermost back contact of B, right hand outermost back contact of R, left hand and right hand coils of relay 100 PI, right hand back contact of relay Y, right hand middle back contact PII, test brush *c*_{II}, test line *c*23, coil of relay T23 to - pole of battery.

PI and T23 are energized. While T23 disconnects the line relay R23 from the called subscriber's line, PI makes the line "busy" for local connections by short circuiting its left hand high resistance coil at its innermost 105 front contact.

The slow release relay V releasing its armature after the energization of PI connects at its right hand middle back contact the right hand coil of relay PII for the light armature in parallel with the low resistance right hand coil of the test relay PI. The right hand coil of PII has been chosen in such manner that the light armature of PII, shown at the left hand side of the relay, is attracted and closes its front contact. This prepares the bringing into circuit of the second left hand coil of PII for the heavy armature. This coil is brought into circuit if, after the said second controlling impulse, the relays B and V are 115 re-energized. The circuit for the left hand coil of relay PII is as follows:

- + pole of battery, right hand outer front contact A, left hand contact of PII, third right hand front contact B, right hand inner 120 coil of PII to - pole of battery.

front contact of relay V, left hand coil of PII — pole of battery.

The heavy armature of PII switches over the relay PI by means of the middle right hand front contact of PII into the local circuit through the resistance coil α , while the outermost right hand contact of PII directly connects the test line $c23$ through cII to the plus terminal, so that the subscriber's line is now made "busy" both for local and toll calls.

PI remains energized independently of the switching operations of the relay PII and closes the circuit for the automatic ringing up of the subscriber and for a free or idle signal to the toll operator. The ringing up circuit is as follows:

— pole of battery, left hand coil Q, second front contact from the left of relay PI, brush aII , wire $a23$ of the subscriber's line, subscriber station No. 23, wire $b23$ of the subscriber's line, brush bII , resistance coil u , third front contact from the left of PI, right hand inner front contact of PII, alternating current source to + pole of battery.

The relay Q is not energized by the ringing current as its right hand coil is short circuited by means of the right hand back contact of relay Y. The ringing up current is periodically switched on and off in the usual manner by an automatic interrupter (not shown) arranged outside the final selector. During the interval between two ringing periods, the b -branch of the subscriber's line is directly connected with the plus terminal. A buzzer current for the free signal to the operator passes through the circuit:

+ pole of battery, f. s. (free signal), left hand outer front contact of PI, right hand inner front contact of A, right hand coil of the relay B, left hand coil of the relay A to the other terminal of f. s. — pole of battery, and is transmitted by means of the other coils of the relays A and B to the operator 45 at the toll exchange. The free signal is interrupted and closed by the interrupter referred to above at the same time as the ringing current.

If the subscriber No. 23 answers, the relay 50 Q is energized by the direct current passing through its left hand coil and passing through both branches of the line in series upon lifting the receiver at the station No. 23. Q when energized closes the talking circuit through the connector LW at its left hand middle and inner front contacts and it also connects at these contacts the relay Y to line $b23$. The relay Y is energized and 55 interrupted by opening its left hand back contact the circuit of the relay A1 at the position of the toll operator, which, when de-energized, opens its front contact the circuit of a supervisory lamp SL, so that the 60 operator sees from the extinguishing of the said lamp SL that the called subscriber 65

answers. The relay Y also opens at its right hand back contact the short circuiting path for the right hand coil of the relay Q, so that this coil helps in maintaining the relay energized. The relay Q causes the relay PI to be de-energized by short circuiting it at its right hand front contact, so that the ringing up and the free signal are terminated. The energizing left hand coil of the relay Q is switched parallel to the right hand coil 70 of relay PII at the second back contact from the left of PI and therefore assists its attraction. The connection between the subscriber No. 23 and the toll exchange is thus maintained even if the subscriber de-energizes the relay Y by hanging up his receiver and causes a short circuiting of the right hand coil of Q.

(b) *When the subscriber's line is "busy" with a local connection*

Under these circumstances the relay PI is not energized as in the selector WL1 of the local exchange connected to the line, the wire $c23$ is already connected to the plus terminal through the low resistance upper coil of the relay P of the said selector WI in Fig. 3. The relay PII however, as before, is able to attract its light armature after the slow release relay V has been deenergized. The different behaviour of the two testing relays PI and PII produces the following action, differing from that described under (a).

The ringing current circuit is not closed and instead of a free signal, a "busy" signal 85 is transmitted to the talking conductors of line LI by the following circuit:

+ pole of battery, from b. s. (busy signal), right hand middle back contact of R, left hand outer back contact of PI, right hand inner contact of A, right hand coil of B and left coil of A (buzzer coils) — pole of battery.

This busy signal is heard by the operator as before. After the closing of the left front contact of PII the relay Q is immediately energized as follows:

+ pole of battery, right hand front contact of A, left hand front contact of PII right hand inner back contact of V, second back contact PI from the left, left hand coil of Q to — pole of battery.

The a - and b -branches of the line LI and of the subscribers line respectively upon energization of the relay Q are already connected during the controlling impulse referred to above. The subscribers both hear the busy signal, warning them that they are going to be disconnected.

The breaking down of the local connection is effected at the end of the controlling impulse when the left hand coil PII acting upon the heavy armature becomes operative and directly connects, as before, the wire $c23$ to the plus terminal. By this, apart from

the above mentioned making "busy" of the subscriber No. 23 for local and long distance calls, the relay P (Fig. 3) of the selector WI connected with the wire c23 is deenergized by short circuiting and the local conversation is cut off at the contacts of this relay, only the called subscriber No. 23 remaining connected to the toll exchange. In order to terminate the "busy" signal, when the local connection is broken down as upon re-energizing of the relay B at the end of the controlling impulse, the left hand inner back contact of B is opened producing deenergization of the relay A (and A1), already prepared by the opening of the left hand back contact of the relay Y, so that the contact of relay A in the "busy" signal circuit is also opened.

20 (c) *When the line of the subscriber No. 23 is busy with a toll connection*

In this case, neither of the testing relays PI and PII is energized as the wire c23 is already directly connected to earth by another connector such as LW adjusted to the line by the toll exchange. Therefore, the relay Q cannot be energized and the automatic operations hereinbefore referred to under (a) and (b) do not take place except 30 the switching on of a busy signal. In the case (c), the toll operator is in a position to complete the connection by repeating the controlling impulse without a repeated operation of the connector as soon as the called 35 subscriber is no longer "busy" with the previous toll call.

As in either case the connection of the subscriber with the toll exchange is secured independently of the supervisory relay Y, 40 the subscriber can give flashing signals to the toll operator by vibrating or jogging his receiver hook without releasing the final selector.

The toll operator can again ring up a 45 called subscriber who has answered but has prematurely hung up his receiver, simply by repeating the controlling impulse. The relay B deenergized by this impulse will open at its third right hand back contact thus interrupting the circuit of relay Q, so that the circuit arrangement will again be brought into the same state as after the first testing operation.

The toll operator recognizes from the 55 supervisory lamp SL and the free or busy signal given over the line LI, the condition of the called subscriber's line. If the line is free, then the lamp SL is lighted after the controlling impulse has ceased until the 60 called subscriber answers as the relay A1 is energized by the following circuit:

+ pole of battery, coil of A1, a-branch of the line LI, left hand back contact of Y, right hand coil of A to - pole of battery.

65 If the called line is "busy", then the super-

visory lamp SL is extinguished after the controlling impulse as the circuit of the relay A1 is interrupted at the above mentioned contact of relay Y. If the subscriber's line is busy with a toll call, then the supervisory lamp SL remains lighted as with a free line, but the toll operator receives the busy signal over the line LI.

The connector can be influenced by the calling party by shortening of the controlling impulses in such manner that it acts in the same way as an ordinary connector switch for local traffic, or in other words, so that it can only be set upon free lines and prevents the called subscriber connected up for a toll connection from being connected to other lines. The controlling current impulse in this case must be so shortened that the slow release relay V is unable to release its armature and to switch on the testing relay PII. By thus making PII inoperative, all the switching operations for toll traffic are prevented from taking place. This feature of the improved circuit arrangement can be applied in such manner that when the simple circuit arrangement of my present invention is used, an automatic exchange is provided with only one type of final selector.

If the connector is used for a toll connection, it is then advisable to apply another periodicity for the ringing current so that it is possible to recognize by the ringing that the toll exchange is calling. This switching over from one periodicity to another is effected by the toll test relay PII at its right hand inner contact.

The release of the final selector in case of a toll connection is always effected by the operator. By withdrawing the cord line plug from the jack of the line LI, the relays A and B are deenergized, and the relay Q is also deenergized. The lifting magnet H then receives current impulses and brings the connector switch into its position of rest by the following circuit:

+ pole of battery, a current interrupter (not shown), foot contact w, left hand outer back contact of Q, left hand outer back contact of B, left hand back contact of A, coil H to - pole of battery.

In the case of local connections, or if the switching on of the relay PII has been prevented by shortening the controlling impulse, the connections are released in the same manner but in this case the called subscriber can 120 free his line by deenergizing the relays Y and Q by hanging up his receiver.

Having fully described my invention, what I claim as new and desire to secure by Letters Patent of the United States is:—

1. In a telephone system having calling and called subscribers' lines, a toll operator's position having incoming toll lines and automatic switches controlled by either a calling subscriber or the toll operator for establish-

ing a connection to a called line characterized by the fact that said switches are provided with means for automatically signalling the calling and called subscribers in case the line called by the toll operator is busy and for thereupon automatically breaking the connection to the other subscriber.

2. In a telephone system having calling and called subscribers' lines, a toll operator's position having incoming toll lines and automatic switches controlled by either a calling subscriber or the toll operator for establishing a connection to a called line characterized by the fact that said switches are provided with means automatically operative when the switches are controlled by the toll operator for distinguishing between busy called lines connected to local calling lines or to lines through the toll operator's position.

3. In a telephone system having calling and called subscribers' lines, a toll operator's position having incoming toll lines and automatic switches controlled by either a calling subscriber or the toll operator for establishing a connection to a called line characterized by the fact that said switches are provided with means automatically operative when the switches are controlled by the toll operator for breaking down a local connection and for signalling the toll operator without interrupting the connection when the called line is already engaged in a toll call.

4. In a telephone system having calling and called subscribers' lines, a toll operator's position having incoming toll lines and automatic switches controlled by either a calling subscriber or the toll operator for establishing a connection to a called line characterized by the fact that said switches are provided with restoring means normally controlled over a subscriber's line but controllable automatically through switches adjustable by the toll operator whereby the connection to a called line is maintained if the called subscriber hangs up his receiver or depresses the receiver hook in the case of a long-distance call.

5. In a telephone system having calling and called subscribers' lines, a toll operator's position having incoming toll lines and automatic switches controlled by either a calling subscriber or the toll operator for establishing a connection to a called line characterized by the fact that said switches are provided with restoring means controlled by the toll operator in the case of a long-distance call and that the toll operator's position is provided with means for automatically ringing a called subscriber who hangs up prematurely.

6. In a telephone system having calling and called subscribers' lines, a toll operator's position having incoming toll lines and au-

tomatic switches controlled by either a calling subscriber or the toll operator for establishing a connection to a called line characterized by the fact that said switches are provided with a local test relay and a toll test relay, and that means is provided in connection therewith whereby only the local test relay is operative in the case of a local calling line and both test relays are operative in the case of a call initiated from the toll operator's position, said switches being further provided with means whereby the operation of the local test relay is ignored in the case of a call initiated from the toll operator's position and a prior connection is interrupted except when the toll test relay indicates that the prior connection is a long-distance call.

7. In a telephone system having calling and called subscribers' lines, a toll operator's position having incoming toll lines and automatic switches controlled by either a calling subscriber or the toll operator for establishing a connection to a called line characterized by the fact that said switches are provided with means responsive to controlling impulses of different character depending upon whether said switches are actuated by a local calling subscriber or by the toll operator, said means being operative to automatically complete a connection to a busy called line when the switches are actuated from the toll operator's position.

8. In a telephone exchange system, a connector switch having movable and stationary contacts; toll lines arranged for connection to said movable contacts; local lines terminating in said stationary contacts and arranged for connection to said movable contacts; means operable through any one of said lines for causing said connector to move its movable contacts on the stationary contacts of a desired line; automatic testing means associated with said connector for testing whether the desired line is "idle" or "busy"; automatic guarding means associated with said connector for making the line connected with "busy"; automatic ringing means for ringing up the desired line when "idle"; automatic switching means operable in response to the setting of said connector over a local line for operating said testing, guarding and ringing means; and secondary testing means for determining whether the desired line when "busy" is engaged in a local or toll call, said secondary testing means being adapted to automatically connect said toll line with a called subscriber's line even when "busy" by connecting with another local subscriber's line.

9. In a telephone exchange system, a connector switch having movable and stationary contacts; toll lines arranged for connection to said movable contacts; local lines terminating in said stationary contacts and ar-

- ranged for connection to said movable contacts; means operable by any one of said lines for causing said connector to move its movable contacts on to the stationary contacts of a desired line; automatic testing means associated with said connector for testing the condition of the desired line for "busy" or "idle"; automatic guarding means associated with said connector for making the line connected with "busy"; automatic ringing means for ringing up the desired line when "idle"; automatic switching means operable in response to the setting of said connector over a local line for operating said testing, guarding and ringing means; secondary testing means for testing the local or toll "busy" condition of the desired line; said secondary testing means being adapted to connect the toll line with a called subscriber's line even when "busy" by connecting with another local line; secondary guarding means for making the desired line "busy" for toll calls to other connector switches having access thereto; and automatic switching means operated in response to the setting of said connector over a toll line for automatically operating all said testing, guarding and ringing means and also said secondary testing and guarding means.
- 10 10. In a telephone exchange system, a connector switch having movable and stationary contacts; toll lines arranged for connection to said movable contacts; local lines terminating in said stationary contacts and arranged for connection to said movable contacts; impulse-sending devices in connection with each of said lines for sending a series of numerical impulses and a controlling impulse after each of said series, the impulse-sending devices of the toll lines being adapted to send a longer controlling impulse than those of the local lines; means operated by the numerical impulses of said devices for causing said connector to move its movable contacts onto the stationary contacts of a desired line; automatic testing means operated by the controlling impulse following the last series of numerical impulses; automatic ringing means for ringing up the desired line when "idle"; automatic switching means operable in response to the setting of said connector when adjusted by impulses over a local line for operating said testing, guarding and ringing means; secondary testing means for determining whether the desired line is "busy" on a local or toll call, the last named means being adapted to connect the toll line with a called subscriber's line even when "busy" by connecting with another local line; secondary guarding means for making the desired line "busy" on toll call to other connector switches having access thereto; and automatic switching means operated by the extended controlling impulse of a toll impulse-sending device, following the last series of numerical impulses for automatically operating all said testing, guarding and ringing means and also said secondary testing and guarding means.
- 15 11. In a telephone exchange system, a connector switch having movable and stationary contacts; toll lines arranged for connection to said movable contacts; local lines terminating in said stationary contacts and arranged for connection to said movable contacts; means operable through any one of said lines for causing said connector to move its movable contacts on the stationary contacts of a desired line; a test relay associated with said connector for testing the condition of the desired line for "busy" or "idle"; a second test relay for determining whether the desired line when "busy" is engaged on a local or toll call, said second test relay being energized in response to the setting of said connector over a toll line onto one of the said stationary contacts and being connected with a subscriber's line in immediate connection with another subscriber's line, the energization causing the connection of the desired line with the toll line and interrupting the local connection.
- 20 12. In a telephone exchange system, a connector switch having movable and stationary contacts; toll lines arranged for connection to said movable contacts; local lines terminating in said stationary contacts and arranged for connection to said movable contacts; means operable by any one of said lines for causing said connector to move its movable contacts onto the stationary contacts of a desired line; a test relay associated with said connector for determining whether the desired line is idle or busy; a second test relay for determining whether the line if busy is engaged on a local or toll call, the same being operated automatically in response to the setting of said connector over a toll line; and a contact at said second test relay for connecting a battery potential to the third wire of the desired subscriber's line and thereby short circuiting the first test relays of all other connectors adjusted onto said subscriber's line.
- 25 13. In an automatic telephone system, a combined toll and local connector for use by an operator or by local subscribers in selecting and connecting with called lines; automatic testing means associated with said connector for determining whether the desired line is busy or idle; automatic testing means for determining whether the line when busy is engaged on a toll or local call and for breaking down a connection of the called subscriber with another local subscriber, the same being operated in response to the setting of the connector for a toll operator; and automatic signal means for announcing to the talking sub-

scribers the impending disconnection of the local conversation in favor of a toll call.

14. In a telephone exchange system, a combined toll and local connector for use by an operator or by local subscribers in selecting and connecting with called lines; an impulse-sending device associated with the toll lines controlled by the operator and adapted to send out numerical and controlling impulses;
- 10 means for repeating said controlling impulses; automatic ringing means associated with said connector; and means operated by the repeated controlling impulses for bringing said automatic ringing means again into action.
15. In a telephone exchange system, a combined toll and local connector for use by an operator or by local subscribers in selecting and connecting with called lines; automatic ringing means for ringing up the desired line with a predetermined periodicity when idle, and automatic switching means operable in response to the setting of said connector over a toll line for sending the ringing current with another periodicity.

In testimony whereof I have affixed my signature.

FRIEDRICH MERK.
